UNITED STATES PATENT OFFICE.

CLARENCE O. DUFFY, OF OAKLAND, CALIFORNIA.

MAGAZINE-HOLDER.

968,748.

Specification of Letters Patent. Patented Aug. 30, 1910.

Application filed October 19, 1909. Serial No. 523,471.

To all whom it may concern:

Be it known that I, CLARENCE O. DUFFY, citizen of the United States, residing at Oakland, in the county of Alameda and 5 State of California, have invented certain new and useful Improvements in Magazine-Holders, of which the following is a specification.

This invention relates to temporary binders or covers for magazines and the like, and the principal object of the same is to provide a binder that will have a firm engagement with the magazine, yet readily permit the opening and closing of the same, and 5 which can be easily removed from the magazine when desired.

In carrying out the object of the invention generally stated above, it will be understood, of course, that the essential features of the same are necessarily susceptible of changes in details and structural arrangements, one preferred and practical embodiment of which is shown in the accompanying drawings, wherein:—

5 Figure 1 is a perspective view of the improved binder, shown open. Fig. 2 is a vertical longitudinal sectional view taken on the line X—X, Fig. 1. Fig. 3 is a transverse vertical sectional view taken on the 10 line y—y, Fig. 2. Fig. 4 is a view similar to Fig. 2, but showing a magazine within the binder.

Referring to said drawings by numerals, 1—1 designates the cover leaves of the 15 binder which are connected by the usual flexible back 2. A flat reinforcing strip 3 extends longitudinally of the inner surface of said back 2, said strip having a recessed portion 4 adjacent one end. A flat plate 5 is riveted or otherwise rigidly secured to the inner face of the strip 3, one end of said plate extending well beyond one end of the strip 3 and provided with an opening 6 by 20 means of which the binder may be suspended 45 from a nail, hook, or other support. The plate 5 has outstanding side flanges 7 which are arranged on a slight inward inclination, said flanges being of the same length as the strip 3, one end of each flange flaring outwardly as indicated at 8 to provide a tapering entrance way between said flanges which 25 facilitates the sliding of the back of a magazine therein.

A flat leaf spring 9 is located within the 30 recess 4 of the strip 3, one end of said spring being riveted or otherwise rigidly fastened

to said strip, the other end of said spring being bent at right angles thereto to provide a locking tongue 10 that projects through an opening 11 in the plate 5 and is adapted for 60 interlocking engagement with a notch 12 formed in the back 13 of the magazine.

To place a magazine in the binder, the back thereof is notched and then pushed through the flaring entrance way of the 65 gripping flanges 7, the locking tongue 10 of the spring 9 being held depressed until the back of the magazine passes thereover and brings the notch into position where it will be engaged by said locking tongue. To re- 70 lease the magazine, a knife or the like may be passed between the pages to force the tongue 9 from engagement with the notch in the back of the magazine, whereupon, the said back may be readily slid from between 75 said flanges.

What I claim as my invention is:—

1. A device of the character described comprising a pair of cover leaves, a flexible back connecting the same, a recessed reinforcing 80 strip mounted on said back, a plate covering said strip and provided with gripping flanges, said plate being also provided with an opening which communicates with the recess of said strip, and a spring within said 85 recess having one end fastened to said plate the other end of said spring being bent at right angle to provide a locking tongue that normally projects through the opening of said plate for engagement with the back of 90 a magazine.

2. A device of the character described comprising a cover, a plate carried thereby and provided with outstanding gripping flanges, one end of said flanges being outwardly 95 flared, and a spring tongue projecting through said plate for detachable locking engagement with a magazine held between said gripping flanges.

3. A device of the character described comprising cover leaves having a flexible back connection, a reinforcing strip carried by said back, a plate mounted on said strip and having a projecting end provided with a suspending opening, gripping flanges carried 100 by the side of said plate, and a locking tongue projecting through said plate.

4. A device of the character described comprising cover leaves, a back therefor, a plate carried by said back, outstanding inwardly 110 inclined gripping flanges at the side of said plate, one end of said flanges being outwardly

flared, and a locking tongue projecting through said plate for engagement with a magazine between said flanges.

5. A device of the character described comprising cover leaves, a back therefor, a reinforcing strip carried by said back and provided with a recess, a holding plate mounted on said strip and provided with an opening, a spring in said recess and having one end fastened to the under surface of said plate, the other end of said spring being bent at

right angles to provide a locking tongue that normally projects through said opening and adapted for engagement with the back of an article seated on said plate.

1

In testimony whereof I affix my signature in presence of two witnesses.

CLARENCE O. DUFFY.
